UNITED STATES PATENT OFFICE.

JOHN M. MILLS, JR., OF TISKILWA, ILLINOIS.

CONVERTIBLE LADDER.

1,250,615.

Specification of Letters Patent. Patented Dec. 18, 1917.

Application filed April 12, 1915. Serial No. 20,819.

To all whom it may concern:

Be it known that I, JOHN M. MILLS, Jr., a citizen of the United States, residing at Tiskilwa, in the county of Bureau and State 5 of Illinois, have invented certain new and useful Improvements in Convertible Ladders, of which the following is a specification.

This invention contemplates an improved 10 convertible ladder and has as its primary object to provide a construction which may be employed as a step ladder, as an ordinary wall ladder, or as an improved staging support.

15 The invention has as a further object to provide a construction wherein detachable standards or legs will be employed which will be adjustable upon the body of the ladder so that the ladder may be readily used 20 upon an inclined surface or upon a staircase.

25 The invention has as a further object to provide an improved connection between the detachable standards and the body of the ladder which, while permitting the standards to be readily detached, will be of such construction that under ordinary circumstances, accidental displacement of the standards will be reduced to a minimum.

30 The invention has as a further object to provide a construction wherein the standards and the body of the ladder will be adapted to coact to provide an efficient form of staging support, in the nature of a tripod 35 and wherein one leg of the ladder will be provided with an extension, so that the tripod may be readily adjusted to rest firmly upon uneven surfaces.

And the invention has as a still further 40 object to provide an improved spacing bar and mounting therefor to be used in connection with the tripod or staging support and wherein said bar will be adapted to engage the wall of a building for holding the 45 tripod in spaced relation thereto.

Other and incidental objects will appear as the description proceeds and in the drawings wherein I have illustrated the preferred embodiment of the invention and 50 wherein similar reference characters designate corresponding parts throughout the several views.

Figure 1 is a perspective view showing the device arranged in the form of a stepladder,

Fig. 2 is a similar view showing the ladder adjusted for use upon a staircase,

Fig. 3 is a perspective view showing the ladder arranged to form a tripod adapted to provide a staging support,

Fig. 4 is a similar view showing the ladder folded for shipment or storage,

Fig. 5 is a fragmentary perspective view showing the ladder arranged to form a tripod,

Fig. 6 is a fragmentary perspective view showing the mounting of the rack bar carried by the extension arranged to coact with one of the rails of the ladder,

Fig. 7 is a side elevation showing the wedge mounted upon the leg of the ladder and adapted to coact with the rack bar for holding the extension at adjustment,

Fig. 8 is a fragmentary sectional view showing the attaching brackets employed for connecting the supporting standards to the body of the ladder, this view also illustrating the construction of the hook members carried by the said standards,

Fig. 9, is a fragmentary perspective view showing the mounting of the brace rods carried by the standards,

Fig. 10 is a fragmentary perspective view showing the hooks carried by the standards and adapted to coact with the brace rods for yieldably holding the said rods in operative position,

Fig. 11 is a perspective view showing the anchoring member carried by one rung of the ladder and adapted to coact with certain of the brace rods employed,

Fig. 12 is a perspective view showing one of the anchoring members carried by the rails of the ladder and adapted to coact with the brace rods,

Fig. 13, is a perspective view partly broken away and showing a modification of the invention, and

Fig. 14 is a fragmentary perspective view showing the manner in which the standards are connected to one rail of the ladder in the modification shown in Fig. 13.

In the preferred embodiment of the invention, I employ a ladder which includes side rails or legs 10 and 11 respectively, which are connected by a plurality of rungs 12, one of which extends through the said rails to provide laterally projecting lugs 13. Mounted upon the rails 10 and 11 at the upper terminals thereof are brackets 14. 110

The brackets 14 are preferably formed from metal and are arranged to seat flatly against the adjacent upper terminals of the rails 10 and 11 as best shown in Fig. 5 of the drawings 5 with opposite extremities thereof secured, in any suitable manner to opposite longitudinal edges of the rails. Upon one side of the ladder, the brackets 14 are formed to provide substantially U-shaped loops 15 extending laterally from the rail 10 and in the lower side portion 16 of each of which is provided a suitable opening. The openings are arranged in alinement and their purpose will presently appear.

15 Seated upon the upper extremities of the rails 10 and 11 is a cap board 17, the said cap board being arranged to rest upon the adjacent portions of the brackets 14 extending across the upper end of the rails and being secured to the rails by a plurality of screws or other suitable fastening devices 20 extending through the cap board and through the said brackets.

Mounted upon one side margin of the cap board 17 at opposite extremities thereof, are angle irons or guides 18. The guides 18 are preferably formed of metal and may be secured to the cap board 17 in any suitable manner, being arranged with their free terminals projecting laterally away from the cap board 17 in substantial parallel spaced relation to the rails 10 and 11. These guides are more particularly shown in Figs. 3 and 5 of the drawings.

35 Swingly mounted upon the under side of the cap board 17 is a wedge 20 clearly illustrated in Fig. 3, the said wedge being arranged substantially midway the ends of the cap board and being swingingly connected therewith by a suitable pivot pin 21. The purpose of this wedge will also presently appear.

Mounted upon the rail 11 of the ladder adjacent the lower extremity thereof, are 45 longitudinally spaced laterally projecting guide loops 22 and 23 respectively. Each of these loops is preferably constructed from a single strip of metal bent into substantially rectangular form and arranged to embrace the rail 11 in the manner best shown in Fig. 1 of the drawings, the said loops being secured to the rail in any suitable manner. Pivotally mounted upon the guide loop 23 and arranged to confront the inner 50 longitudinal edge of the rail 11, is a wedge 24 shown in detail in Fig. 6 of the drawings.

The guide loops 22 and 23 are adapted to freely receive an extension 25. The extension 25, adjacent one end thereof, is cut away as shown in detail in Fig. 6 of the drawings to receive a rack bar 26.

60 The bar 26 is preferably formed from a single piece of metal and is suitably secured 65 to the extension, being arranged to project,

at its free edge, laterally upon one side thereof.

As will now be clear, the extension 25 is adjustable longitudinally of the rail 11 within the guides 22 and 23 and the bar 26 is 70 adapted to engage the guide 23 for holding the said extension at adjustment. In this connection, it will be noted that the wedge 24 is arranged to coact with the rack bar, being adapted to engage between the adjacent 75 portion of the said guide and the inner longitudinal edge of the extension for moving the extension laterally within the said guide, with the teeth of the rack bar in engagement with the portion of the guide opposite the said wedge.

As will be clear, the extension 25 may be locked at longitudinal adjustment through the medium of the wedge 24 upon the rail 11 and may be readily removed from the rail 80 when desired.

Mounted upon opposite longitudinal edges of the rail 10 adjacent the upper extremity thereof and in spaced relation to the contiguous bracket 15 carried by the rail, are 90 oppositely disposed attaching brackets 27 more particularly shown in Fig. 8 of the drawings. Each of the brackets 27 is preferably formed from a single piece of metal which is bent adjacent one end to provide a 95 spur 28 seating within the rail 10, and at its opposite extremity to provide a terminal apertured lug 29 extending laterally away from the contiguous edge of the rail. It will be noted that the intermediate portions 100 of the brackets are flat and adapted to seat against opposite edges of the rail 10 and the said brackets are detachably connected with the rail by a bolt 30 extending therethrough as shown in detail in Fig. 8. The particular 105 function of these brackets will also presently appear.

Arranged to coact with the body of the ladder are standards 31. The standards 31 are each preferably cut away at one end and 110 detachably connected thereto are hooks 32. The hooks 32 are best shown in Fig. 8 of the drawings and it will be noted that each of said hooks is provided with a bill extending in angular relation to the shank 33 115 thereof. The shanks 33 are provided with laterally directed terminals which are passed through the adjacent ends of the standards and are screw threaded to receive nuts 34. Connecting the shanks 33 of the 120 hooks with the standards intermediate the ends of said shanks are hook bolts 35. It will be noted that the shanks 33 of the hooks project beyond adjacent ends of the standards and the hooks 32 are adapted to engage the apertured ears 29 of the brackets 27 in the manner also best shown in Fig. 8 125 of the drawings, and are further adapted to detachably engage within the openings formed in the portions 16 of the loops 15 in 130

- the manner shown in Fig. 1. In this connection, attention is directed to the fact that when the hooks 32 are engaged with the brackets 27 in the manner shown in Fig. 8, 5 the angularly directed terminals or bills of the said hooks are adapted to extend freely through the apertures of the ears 29 to project laterally over the opposite sides of said ears. The free terminals of the hooks will, 10 therefore, under ordinary circumstances, act to freely connect the standards and the brackets 27, while, at the same time, the said standards may be freely swung upon the brackets. 15 Mounted upon the inner edges of the standards 31 at longitudinally spaced points, are staples 36 and 37 respectively. Arranged to coact with the said staples are pairs of brace rods 38 and 39 respectively, 20 the rods 39 being longer than the rods 38. As shown in detail in Fig. 9 of the drawings, each of the staples 36 is cut away upon one side to detachably receive the open eye of the rod coacting therewith so that the 25 said rods may be readily disconnected from the standards when desired and each of the rods is at its free end, provided with a terminal hook 40, as more particularly shown in Fig. 10 of the drawings. The rods 38 30 and 39 are each preferably formed from a suitable length of resilient metallic rod as are also each of the staples 36, the said staples being driven into the standards in the well known manner. 35 Mounted upon one rung of the ladder adjacent the upper end thereof, or in other words, that end provided with the cap board 17, is an anchoring device 41, which is, as more particularly shown in Fig. 1 of the 40 drawings, arranged substantially midway the ends of the said rung. The anchoring device 41 as shown in detail in Fig. 11, is preferably formed from a single length of suitable resilient wire 45 bent intermediate its ends to provide laterally disposed eyes 42 which are joined by a connecting portion 43 and which merge into substantially parallel prongs 44. The prongs 44 are driven through the said rung 50 of the ladder and are deflected laterally at their free ends for securely connecting the said device with the rung. The eyes 42 are adapted to freely receive the hooks 40 of the rods 38 and 39. Connected to the rails 10 55 and 11 adjacent the lower extremities thereof, are anchoring devices 45 shown in detail in Fig. 12 of the drawings. Each of the said devices also is preferably formed from a single length of wire bent intermediate its 60 ends to provide eyes 46 which are joined by a longitudinally curved connecting portion 47, the said eyes merging into substantially parallel prongs 48. As illustrated in Fig. 5 of the drawings, the anchoring devices 45 65 are preferably arranged at opposite ends of the rung of the ladder immediately adjacent the bottom rung, with the connecting portions 47 of the said devices bearing over the rung in the manner shown in Fig. 12, and with the prongs 48 driven through the rails 10 70 and 11 and deflected laterally at their extremities, for securely connecting the said anchoring devices with the ladder. The eyes 46 are also adapted to freely receive the hooks 40 of the rods 38 and 39. 75
- In Fig. 1 of the drawings, I have shown the standards 31 connected to the body of my improved device to form a stepladder. As therein illustrated, the hooks 32 are engaged within the openings formed in the 80 portion 16 of the loops 15 with the standards extending in outward divergent relation to the rails 10 and 11. The brace rods 38 are connected to the oppositely disposed eyes 36 of the said standards, with the hooks 40 85 thereof connected to the anchoring devices 41 while the brace rods 39 are connected with the oppositely disposed staples 37 of the standards with the hooks thereof engaging the anchoring devices 45. The standards 90 will thus be rigidly supported in spaced relation to the rails 10 and 11 and for maintaining the hooks of the rods 38 and 39 in engagement within the eyes of the anchoring devices, I provide hooks 49, as more particularly shown in detail in Fig. 10 of the drawings. The hooks 49 may be of any suitable character and are each arranged upon one side of the adjacent staple 36 or 37 as the 95 case may be. When the rods 38 and 39 are connected with the anchoring devices 41 and 45, the said hooks will act to bow the rods longitudinally. The rods 38 and 39 being resilient, will thus coact with the hooks 49 to normally urge the hooks of the said rods seated within the eyes of the anchoring devices. 100
- In Fig. 2 of the drawings, I have illustrated the adjustment of the standards relative to the body of the ladder so that the 110 device may be used upon a staircase or other inclined surface. The standards 31 are each provided with series of longitudinally spaced openings 50 adapted to freely receive the lugs 13. The said lugs are positioned within corresponding openings of the said series of openings with the standards projecting obliquely above the cap plate 17 of the ladder to engage the adjacent longitudinal edge of the cap plate and with the retaining lugs 115 engaging transversely over the outer faces of the said standards. It will thus be observed that the said retaining lugs are adapted to maintain the standards in engagement with the lugs 13. When so used, the longer 120 pair of brace rods 39 are preferably disconnected from the standards and the shorter pair 38 thereof are connected in a manner previously described, with the staples 37 with the hooks of the said rods engaging 130

the anchoring device 41. The lower ends of the standards will thus be rigidly connected to the body of the ladder, and it will be seen that when so arranged, the ladder may be 5 readily used for the purposes indicated, the series of openings 50, as will be clear, providing an adjustment for the standards relative to the body of the ladder to thus adapt the structure for use under varying circumstances.

In Fig. 3 of the drawings, I have shown the standards 31 connected to the body of the ladder to form a staging support in the nature of a tripod, the said support being 10 shown as arranged adjacent a wall. The hooks 32 of the said standards are connected to the brackets 27 in the manner previously described with the standards extending in outward divergent relation to the adjacent 15 rail 10 of the ladder to, in effect, form in connection therewith, a tripod. The shorter pair of brace rods 38 are connected to the staples 37 with the hooks of the said rods engaging the anchoring device 45 immediately adjacent the rail 10. The longer pair 20 of brace rods 39 are connected to a pair of staples 51 arranged upon the standards 31 adjacent the staples 37, and are connected to the anchoring device 45 adjacent the rail 25 11 of the ladder. The staples 51 are similar 30 in construction to the staples 36 previously described and are adapted to detachably receive the said rods while hooks 52 similar to the hooks 49 are arranged to coact with the 35 said staples 51.

As will be seen, the standards 31 will thus be rigidly supported in position. The extension 25 is removed from the guide loops 22 and 23 as previously set forth and attention is now directed to the fact that the loops 40 15 are adapted to detachably receive the said extension with the rack bar 26 coacting with one of the said loops as shown in Fig. 3 of the drawings. As therein illustrated, the 45 extension is of a length to project laterally beyond the side of the body of the ladder opposite the standards 31 and may be adjusted through the medium of the rack bar 26, the teeth of the rack bar being adapted 50 to engage the adjacent loop. The purpose of the wedge 20 now becomes apparent, since the said wedge is adapted to be moved upon its pivot to engage between the cap plate 17 and the adjacent longitudinal edge of the 55 extension for urging the rack bar into operative coacting relation with the said loop, and to consequently coact with the rack bar and with the cap plate for locking the extension at adjustment.

60 As shown in Fig. 3, the extension will thus be mounted upon the body of the ladder to contact with a wall for supporting the adjacent upper end of the ladder away from the wall, while the standards 31 will support the rails of the ladder in spaced rela-

tion to the ground or other supporting surface. My improved ladder will thus provide an efficient form of staging support which may be readily assembled to be placed in position, or which may be as easily removed when desired.

In Fig. 4 of the drawings, I have illustrated the several elements of the device folded for storage or shipment. It will be remembered as previously described, that the standards 31 are swingingly connected with the brackets 27 through the medium of the hooks 32 carried by the said standards, and as illustrated in this figure, the standards are swung upon the said brackets 75 80 in opposite directions to seat against opposite sides of the body of the ladder. Connecting the standards adjacent the outer ends thereof, is a hook 53 swingingly connected with one of the standards and adapted 85 to engage the eye carried by the other standard. The brace rods 38 are arranged to extend from the staples 37 and are connected to the anchoring device 45 arranged adjacent the rail 10, while the brace rods 90 39 are connected to the staples 51 and are engaged with suitable eyes 54 carried by the standards, the said last mentioned brace rods being thus arranged to seat flatly 95 against the inner faces of the standards. The standards and brace rods being so disposed, the extension 25 is arranged in inactive position upon the rail 11, so that the entire device will occupy a minimum space.

In Fig. 5 of the drawings, I have shown the standards arranged upon the body of the ladder to provide a tripod adapted for general use. The standards are connected to the brackets 27 in the manner therein illustrated. The brace rods 38 and 39 are 100 105 arranged as above described with particular reference to the use of the invention shown in Fig. 3 of the drawings, and the extension 25 is moved into active position upon the rail 11. When so disposed, the said extension will, as will be readily seen, coact with the standards to form a very efficient type of tripod.

In Figs. 13 and 14, I have disclosed a slight modification of the invention as used 115 in connection with a conventional type of wall ladder indicated at 55. Mounted upon one rail of the ladder is an attaching plate 56 which is provided with spaced pairs of aligned openings 57, the said rail being recessed in the rear of the said openings. Arranged to coact with the ladder are standards 58 which, at their upper extremities, are provided with hooks 59 similar in construction to the hooks 32 of the preferred 120 form of the invention. The hooks 59 are adapted to detachably engage within corresponding aligned openings 57 of the plate 56 for detachably connecting the standards 125 with the ladder.

Connected to opposite rails of the ladder and arranged at opposite ends of the bottom rung thereof are the anchoring devices 45 and the pairs of brace rods 38 and 39 are arranged to extend between the free ends of the standards and the said fastening devices in the manner more particularly shown in Fig. 13. The standards will thus coact with the ladder to, in effect, provide a tripod 10 adapted to form a staging support similar to that disclosed in Fig. 3 of the drawings, and for spacing the upper end of the ladder from a wall or other surface, I provide a spacing member 60. Since the detail construction of this spacing member was set forth in Patent No. 1,115,559, issued to me Nov. 3, 1914, a further description thereof, in this connection, is unnecessary. However, it will be observed that the standards 15 will support the ladder in spaced relation to the ground or other supporting surface to rigidly hold the ladder against the wall.

In this modified form of the invention, the standards 58 are each provided with a pair of longitudinally spaced guide loops 61 and 62 similar to the loops 22 and 23 of the preferred form of the invention, the guide loops 62 of each of the standards being provided with a wedge 63 adapted to 30 coact with the extension 64 similar to the extension 25. The effective length of the standards 58 may thus be varied as desired.

It will therefore be seen that I provide a very simple and efficient construction for 35 the purpose set forth wherein the several elements of the device may be assembled to form a step ladder; may be adjusted for use upon a staircase, or other inclined surface; may be assembled to form a tripod; 40 may be arranged to provide a staging support, and may also be easily folded for storage or shipment.

Having thus described my invention, what I claim and desire to secure by Letters Patent is:—

1. In a ladder support, an attaching plate carried by one rail of the ladder and provided with spaced pairs of alined openings, the rail being recessed in the rear of said 50 openings, anchoring devices carried by the ladder, standards, hooks carried by the standards and adapted to respectively engage in alined pairs of openings in the attaching plate, and brace rods adapted to 55 engage said anchoring devices for connecting the standards with the ladder.

2. In a ladder support, attaching brackets carried by one rail of the ladder, standards connected to said brackets to diverge outwardly from said rail and independent with respect to each other, anchoring devices carried by the ladder, brace rods connected to 60 said standards and engaging said anchoring devices for supporting the free extremities 65 of the standards against swinging move-

ment, alined guide loops carried by the rails of the ladder, and an extension received in said guide loops to project upon one side of the ladder opposite said standards and adapted to coöperate therewith in supporting the ladder. 70

3. In a ladder support, alined guide loops carried by the rails of the ladder, standards connected to a rail of the ladder and diverging outwardly away therefrom, said standards being independent with respect to each other, brace rods connecting the standards with the ladder for supporting the free extremities of the standards against swinging movement, a cap-board carried by the ladder, an extension received within said guide loops to project laterally upon one side of the ladder opposite said standards and adapted to coöperate with the standards in supporting the ladder, a rack carried by the 75 extension and engaging one of said loops, 80 and a wedge carried by the cap-board and engaging between the board and said extension at a point intermediate the loops for holding the extension fixed upon the 85 loops. 90

4. In a ladder support, attaching brackets carried by a rail of the ladder, standards connected to said brackets to diverge outwardly from the said rail and independent 95 with respect to each other, brace rods connecting the standards with the ladder and supporting the free ends of the standards against swinging movement, and an extension carried by the other rail of the ladder 100 and coöoperating with said standards to form a tripod.

5. In a ladder support, oppositely disposed attaching brackets mounted upon opposite longitudinal edges of one rail of 105 the ladder, a fastening device extending through the rail and said brackets and connecting the brackets with the rail, the brackets being provided with laterally directed terminals extending in opposite directions from the rail, standards independent 110 with respect to each other, hooks carried by said standards and swingingly connected to the terminals of said brackets, and brace rods connecting the free extremities of the 115 standards with the ladder and supporting the standards against swinging movement.

6. In a ladder support, standards arranged to coöperate with the ladder and independent 120 with respect to each other, brace rods connecting the standards with the ladder for supporting the free extremities of the standards against swinging movement, and an extension carried by the ladder with the extension operable to coöperate with said 125 standards to form a support for the ladder.

7. In a device of the character described, a ladder provided with side rails, a cap board arranged at the upper extremities of the said rails, and a bracket interposed be- 130

tween one of said rails and the said cap board and formed to provide a loop.

8. In a ladder support, standards connected to a rail of the ladder to diverge outwardly therefrom, the said standards being independent with respect to each other, anchoring devices carried by the ladder, and brace rods connected to said standards and engaging said anchoring devices for supporting the free extremities of the standards

against swinging movement with the said standards disposed to coöperate with the ladder to form a support therefor.

In testimony whereof I affix my signature in presence of two witnesses.
